OPERATING LEVER FOR AN ELECTRICAL SWITCH

Harry J. Collins, Jr., Bayside, Wis., assignor to Cutler-Hammer, Inc., Milwaukee, Wis., a corporation of Delaware

Filed Mar. 30, 1965, Ser. No. 84,519

Term of patent 14 years

(Cl. D26—13)

Fig. 1

Fig. 2

Fig. 3

Fig. 4

FIGURE 1 is an isometric view of an operating lever for an electrical switch showing my new design;

FIG. 2 is a side elevational view;

FIG. 3 is an end elevational view; and

FIG. 4 is a top view.

The portions shown in dotted lines are included for purposes of illustration only.

I claim:

The ornamental design for an operating lever for an electrical switch, substantially as shown and described.
